UNITED STATES PATENT OFFICE.

JAMES McALLISTER AND HOWARD E. BARLOW, OF PROVIDENCE, RHODE ISLAND.

AUTOMATIC WATER-RETURN APPARATUS.

SPECIFICATION forming part of Letters Patent No. 623,554, dated April 25, 1899.

Application filed June 24, 1898. Serial No. 684,364. (No model.)

To all whom it may concern:

Be it known that we, JAMES McALLISTER and HOWARD E. BARLOW, of Providence, in the county of Providence and State of Rhode Island, have invented certain new and useful Improvements in Automatic Water-Return Apparatus; and we do hereby declare that the following is a full, clear, and exact description thereof, reference being had to the accompanying drawing, and to the letters of reference marked thereon, which forms a part of this specification.

This invention relates to returning of the water of condensation which forms in steam-supply pipes back to the boiler or generator by gravity.

The object of the invention is to form a closed system which will conduct this water of condensation back to the generators at nearly the initial temperature without loss and without the use of pumps, steam-traps, or like moving mechanism.

The mechanism illustrated (partly in section) in the accompanying drawing represents the system attached to and taking the water of condensation from the main steam-pipe of an engine and conveying it back to the boiler.

The steam in passing from the generator A through the main steam-pipe B to the engine C naturally has a large amount of condensation, particularly if the steam is carried to any considerable distance. Wet steam and water, as is well known, are very detrimental to the action of an engine if they are allowed to enter the cylinders. Therefore the condensation is collected in the well v just before it reaches the engine and is conducted down through the pipe d into the receiver e. The steam which has formed a pressure in the receiver rushes up through the riser f, carrying the water with it in small particles. This falls into the straining-chamber g, which is inclosed in the receptacle n, and water here leaves the steam by passing through the openings in the straining-chamber and falls to the bottom of the receptacle h, leaving the dry steam to rise to the top. The receptacle h is surrounded by jacket w to prevent loss of heat from the water that it may return to the boiler at as high a degree of temperature as

possible. The free steam which has passed to the top of the receptacle is conducted by the smaller pipe k down through the injector l, taking in the necessary quantity of water from water-supply pipe m and going directly into the lower part of receiver through the check-valve n. A petcock s is attached to the overflow-pipe t of the injector l for the purpose of drawing off the water, if occasion requires.

The operation is as follows: The steam and its water of condensation flow from the main steam-pipe B or well v down into the receiver e. The steam, passing rapidly over the water lying in the bottom of the receiver, rushes up the riser-pipe f, carrying with it a portion of the water in highly-communited particles, which go into the receptacle above, where the steam and water separate by passing through the straining-chamber g. The water r falls to the lower end, whence it passes into the boiler by its own gravity. The steam separated from the water passes out from the top of the receptacle and around through pipe k and injector l into the lower part of the receiver e, taking water in with it from the supply-pipe m, and is again carried up the riser-pipe f, with the water of condensation that is continually flowing in from the main steam-pipe B going through the receptacle n into the boiler, as above explained.

While this system works well on stationary steam-power plants, it is particularly adapted to steamboats, as the rolling of the vessel often causes an excess of water to flow over into the steam-mains, and by collecting and returning this water to the boilers it insures safety to the engines by keeping it from going into the cylinders, and also avoids the necessity of blowing off the salt water as often as would otherwise be the case if this fresh water of condensation were not returned to the boilers. The injector being attached to the receiver makes the system also act as a high-steam feed-water heater, which in practice is found to be very advantageous. This makes a perfect working close system, operating without perceptible loss and without the objectionable noise of escaping steam.

Having thus described our improvements,

we claim as our invention and desire to secure by Letters Patent—

1. In a closed gravity return system, the combination of a steam-boiler a steam-engine and steam-supply pipe connecting said boiler with said engine, with a receiver, a pipe connecting said supply-pipe with said receiver, a steam and water receptacle situated above said receiver, a straining-chamber inclosed 5 in said receptacle, a vertical pipe connecting said receiver with said straining-chamber, a pipe connecting said receptacle with said steam-boiler, an injector connected to the lower part of said receiver, a smaller pipe connecting upper part of said receptacle with said injector, and a water-supply pipe connected to said injector, substantially as described.
2. In a closed gravity return system, the combination of a steam-boiler a steam-engine a steam-supply pipe connecting said boiler with said engine, and a well attached to said supply-pipe, with a receiver a pipe connecting said well with said receiver, a straining-chamber to separate the steam from the water, inclosed in a receptacle, a steam and water receptacle situated above said receiver, a pipe connecting said receiver with said straining-chamber through the upper end of 25 receptacle, a pipe connecting the lower end of receptacle with said boiler, and pipe leading from top of said chamber, substantially as described.
3. In a closed gravity return system, for steam-boilers, and steam-engines, the combination of a receiver a pipe connecting steam-supply pipe with said receiver, a steam and

water receptacle situated above receiver, a steam and water separating device supported within said receptacle, an upright pipe connecting said receiver with said steam and water separating device through the upper end of said receptacle, a pipe connecting the lower end of said receptacle with said steam-boiler, a pipe to conduct the steam from the upper 45 end of said receptacle down through an injector and check-valve into said receiver, with said injector and check-valve substantially as described.

4. In a closed gravity return system, for steam-boilers, and steam-engines, the combination of a receiver, a steam-supply pipe a pipe connecting said steam-supply pipe with said receiver, a steam and water separating receptacle situated above said receiver, and 50 said generator, an upwardly-extending pipe connecting said receiver with the upper end of said receptacle, a pipe connecting the lower end of said receptacle with said steam-boiler, an injector and check-valve connected to the 55 receiver a pipe to conduct the steam from the upper end of said receptacle down through said injector and check-valve, a pipe connected to a supply of water at a lower temperature for supplying water to said injector, substantially as described.

In testimony whereof we have hereunto set our hands this 23d day of May, A. D. 1898.

JAMES MCALLISTER.
HOWARD E. BARLOW.

In presence of—

BENJ. ARNOLD,
E. B. READ.
